UNITED STATES PATENT OFFICE.

JESSE C. JOHNSON, OF OAKLAND, CALIFORNIA, ASSIGNOR TO S. T. JOHNSON CO., OF OAKLAND, CALIFORNIA.

OIL-BURNER CONSTRUCTION.

Application filed January 23, 1926. Serial No. 33,284.

My invention has its application to an improvement in oil burner construction, particularly of the type employing a horizontally disposed rotary distributing cup and an air pressure means, enabling the supplying to a fire box of a finely divided oil spray for intermixture with the required air for combustion.

The object of the present invention is to 10 provide a manually operated adjustable nozzle for the control of the air blast delivered to the revolving distributing-cup by a blower system.

To provide an air blast controlling nozzle, 15 simple of construction, efficient in action, durable and one wherein worn parts may be quickly replaced.

To more fully comprehend this invention, 20 reference is directed to the accompanying drawings, wherein:

Figure 1 is a vertical sectional view of the adjustable air nozzle, illustrating its position within the burner casing, (here only shown in fragment) and its relation to the 25 distributing cup;

Fig. 2, a side elevational view of the outer side of the burner casing detail, illustrating the air nozzle adjustment;

Fig. 3, a detail of a cross sectional view of 30 the burner casing upon line III—III of Fig. 4, illustrating the manually actuated adjusting means of the nozzle member; and

Fig. 4, a central sectional view through 35 the burner structure, illustrating the operative relation of the adjustable nozzle member therein.

Referring to the drawings, the present device is herein shown in connection with the discharge end of the burner casing 5, forming 40 a tapered mouth portion, ending into an annular air nozzle 6. Formed interior of the burner casing 5 and spaced therefrom, is an annular direction plate member 7, forming an outlet passage 8, for the air blast from 45 a fan blower F shown in Fig. 4 and provided with air ports 11a. The outer end of said direction plate member 7, is inwardly formed to provide a tubular extension 9. A closing plate member 10, provided with a 50 plurality of circular openings 11, serving as air ports, serves as an end member to said tubular extension 9.

Slidably mounted within the tubular extension 9 is the annular air nozzle member 55 12, having a tapered and slightly contracted

mouth portion 13 on its outer end and extending approximately to the forward edge of the fuel distributing cup 14, being in a marginal spaced relation to both, the distributing cup 14 and to the casing nozzle 6. 60 This construction is of considerable importance in preventing the adjustable nozzle member from sticking "freeze" to the supporting casing part of the burner.

From time to time it may be desirable to 65 vary the effective opening of the air nozzle 6 according to conditions as required. To accomplish this in the present instance, this annular air nozzle is provided. This air nozzle member may be given a slidable ad- 70 justment to advance the same, as indicated in dotted lines in Fig. 1, in order to reduce the air blast opening surrounding the distributing cup, thus reducing the volume of 75 the air blast to the fire box, or to retract the same to increase the air blast needed for combustion.

To adjust the air nozzle member 12 for 80 this purpose, suitable means may be provided, in the present instance, in the form of a shaft 13, extending through the casing 5 and through the direction member 7 and having bearing therein, the inner end of said shaft being reduced to some extent to form 85 a dog 14, being positioned off center and integral with the shaft 13.

The air nozzle member 12 is provided with 90 a short elongated opening 15, of a size sufficiently large to receive the dog 14 in an operative relation.

The outer end of the shaft 13 is provided 95 with a suitable operating handle, ending in a milled head 16, which may be rocked to impart the slidable adjustments of the air nozzle member 12 to the extent desired. A dog 17 is formed integral with said handle, and adapted to engage with a series of radial indentations 18 on a plate segment 19, secured on the outer side of the burner casing 5. To hold this device secure in its different positions of adjustment, a coil spring 20 is provided, to surround said shaft interiorly of the casing member 5, having bearing at one end against the inner side of said casing member and at the opposite end being 100 secured to said shaft member 13.

The arrangement of this construction is such, that by providing axially alined air ports 11, on the closing plate member 10, the air blast will be caused to pass along 110

both, the interior and the exterior sides of the air nozzle member 12. The impinging air blasts, issuing from the interior and exterior peripheries of the air nozzle member 12, materially adding in further atomizing the fuel oil and throwing the same forward into the fire box.

Having described my invention, what I claim and desire to secure by Letters Patent 10 is:

1. In an oil burner construction, a fuel distributing cup, a conical casing member ending into a nozzle, a blower for said burner having, in combination, an annular 15 directing member interior of said casing member and spaced therefrom to form a conduit for the air blast from the blower, said directing member being provided interiorly with a tubular extension, an air nozzle member of tubular form, having a contracted end portion, slidably mounted within said tubular extension, being in a marginal spaced relation to the casing member nozzle and to the edge of the distributing 20 cup, manually operated means associated therewith to advance said air nozzle member to reduce the air blast exhaust to the fire box, or to retract the same to increase the volume of the air blast.
2. In an oil burner construction having, in combination, a fuel oil distributing cup, a tapered casing member ending into an air nozzle, a blower for said burner, an annular air deflecting member interior of said casing 25 member and in a spaced relation thereto to form a conduit for the air blast from the blower, said air deflecting member being interiorly of a tubular construction, an air nozzle member of tubular construction and

having a contracted outer end portion, slidably mounted within said tubular interior of said deflecting member, being in a spaced relation to the casing member nozzle and to the edge of the distributing cup, means for slidable adjustments of the air nozzle member positioned exterior of the casing member in operative connection therewith, whereby the effective opening of the nozzle, for controlling the air blast, may be varied according to conditions as required and locking means to secure said nozzle member in different positions of adjustment.

3. In an oil burner construction, having, in combination, a fuel oil distributing cup, a tapered casing member ending into a nozzle, a blower for said burner, an annular air deflecting member interior of said casing and in a spaced relation thereto to form a passage for the air blast from the blower, said air deflecting member being interiorly of a tubular construction, an air nozzle member of tubular form and having a contracted outer end slidably mounted within said tubular part, being in a marginal spaced relation to the casing member nozzle and to the edge of the distributing cup, said tubular constructed deflecting member being at its inner end closed by a plate member provided with a plurality of openings serving as air ports for the admission of an air blast interiorly of said nozzle member, means for actuating said nozzle member and locking means to retain said air nozzle member in different positions of adjustment relative to the distributing cup.

In testimony whereof I affix my signature.

JESSE C. JOHNSON.
